(57) **CLAIM**

The ornamental design for a strip freshener wheel tooth, as shown and described.

DESCRIPTION

FIG. 1 is a perspective view of first embodiment of a strip freshener wheel tooth;

FIG. 2 is a front, top, right perspective view of a strip freshener wheel tooth;

FIG. 3 is a rear, bottom, left perspective view of a strip freshener wheel tooth;

FIG. 4 is a front view of a strip freshener wheel tooth;

FIG. 5 is a rear view of a strip freshener wheel tooth;

FIG. 6 is a left-side view of a strip freshener wheel tooth;

FIG. 7 is a right-side view of a strip freshener wheel tooth;

FIG. 8 is a top view of a strip freshener wheel tooth;

FIG. 9 is a bottom view of a strip freshener wheel tooth;

FIG. 10 is a perspective view of second embodiment of a strip freshener wheel tooth;

FIG. 11 is a front, top, right perspective view of a strip freshener wheel tooth;

FIG. 12 is a rear, bottom, left perspective view of a strip freshener wheel tooth;

FIG. 13 is a rear view of a strip freshener wheel tooth;

FIG. 14 is a front view of a strip freshener wheel tooth;

FIG. 15 is a left-side view of a strip freshener wheel tooth;

FIG. 16 is a right-side view of a strip freshener wheel tooth;

FIG. 17 is a bottom view of a strip freshener wheel tooth;

and,

FIG. 18 is a top view of a strip freshener wheel tooth.

Any shading and cross-hatching are not features of the design but are utilized to illustrate the surface contours of the strip freshener wheel tooth design in the drawings. The broken lines in FIGS. 1 and 10 depict environment and form no part of the claimed design.

1 Claim, 14 Drawing Sheets
